Primary Examiner—Edward J. Michael
Attorney—Alexander Mencher

ABSTRACT: The invention relates to refrigerator structure embodying means therein for thawing out frozen or refrigerated foodstuffs within selected time intervals and comprises an accessible chamber within the interior of the refrigerator, provided with adjustable and controlled heating means to effectuate an accelerated defrosting operation. Means are provided to cause air circulation within the said chamber for oxygenation and prevention of heat build-up to approximate defrosting under the normal ambient conditions present in conventional defrosting.

PATENTED MAY 11 1971

3,578,076

FIG. 1

FIG. 2

LUIS CAMEJO
INVENTOR.

BY *Alexander Deenick*
ATTORNEY

THAWING-OUT MEANS FOR REFRIGERATORS

BACKGROUND OF THE INVENTION

The main object of the invention resides in the structural provision of a heating compartment within the interior of a refrigerator to accelerate the time required for thawing out foodstuffs when either frozen or at lower temperatures to accommodate requirements for cooking or consuming purposes. Heretofore, the thawing-out procedure used in the home was to withdraw the refrigerated foodstuff and expose same to ambient temperatures and conditions of the kitchen or other room, sometimes a long or unsanitary process. The invention herein is intended to overcome these objections in a simple, inexpensive, efficient and safe manner.

A further object of the invention resides in the provision of means to add thawing-out structures in present and to add same in future manufactured refrigerators.

Thus, there is provided a compartment inside the refrigerator provided with or without a frozen food locker to be accessible either by a door directly outside the refrigerator or by an inside door accessible in the refrigerator compartment. A compartment inside the freezer locker would not be practical owing to the more contrasting temperatures involved.

The thawing-out or heater compartment is adapted to be provided with a heater energized either electrically or by gas if the refrigerator is gas operated; and the heater may have a temperature range controllable by a dial or the like located outside or in the refrigerator locker, said heater also being capable of cooperating with a conventional time control device.

Said heater compartment may be located at any selective position in the interior of the refrigerator depending upon the general design and functional requirements thereof, and is provided with ducting means to the exterior for maintenance of controllable temperatures and for oxygenation purposes.

Accompanying this specification is a drawing showing a preferred form of the invention wherein:

FIG. 1 is a front view of a refrigerator embodying the invention and being partially broken-away; and

FIG. 2 is a vertical sectional view of FIG. 1 across the plane 2-2 thereof.

In accordance with the invention and the preferred form shown, refrigerator cabinet 10 is shown having a door 10a and having a refrigerator or cooling food storage area compartment 11, a frozen food compartment 12 and a compartment 13 to house the mechanisms required for temperature lowering.

In refrigerator compartment 11 an insulated door 14 gives access to a separate compartment 15 having a bottom

insulated wall 15a and top and rear insulated walls 15b and 15c afforded as shown by the cabinet 10 and in which is located a heater element 16 such as a Calrod unit. Heater leads 17 and 18 are brought from connections made directly to convenient points in the incoming power supply inside compartment 13. Leads 17 and 18 are preferably out of sight at the rear of the refrigerator but accessible for servicing. One lead as shown is interrupted for a series connection through a suitable voltage control device 19 shown in the food storage area or space mounted on a cabinet wall for heater temperature adjustment, and optionally a timer 20 may be introduced in series with the circuit adjacent to the voltage control device 19.

Heater adjustment may be made in accordance with an accompanying chart or booklet which will list temperature and time for defrosting different foodstuffs according to the nature of the food and the bulk of the food package; that is, its general ratio of surface to depth penetration. To maintain the temperature change in the foodstuff under control for all products and to provide oxygenation, a certain amount of heat leakage and exposure for air circulation are necessary, and for this purpose small convection ducts 21 and 22 in insulated wall 15c are provided.

It is understood that minor changes in the structure and operation of the device described may be resorted to without departing from the spirit of the invention and the scope of the appended claims.

I Claim:

1. In a refrigerator, the combination comprising a cabinet with insulated walls and having an access opening in the front thereof and at least one insulated door for said opening leading into a food storage space, an independent heating compartment for time-controlled thawing out of frozen and refrigerated foodstuffs formed within said food storage space and comprised of thermal insulated walls and an insulated door for access thereto, said heating compartment containing heating means, a controlling device for said heating means, convection ducts to the atmosphere to maintain heating temperatures and to oxygenate the said heating compartment.

2. In a refrigerator as set forth in claim 1 wherein at least the top, end and rear walls of the heating compartment is afforded by the said insulated walls of the cabinet.

3. In a refrigerator as set forth in claim 1 wherein the access door to the heating compartment is located in the food storage space.

4. In a refrigerator as set forth in claim 1 wherein the access door to the heating compartment is located in the food storage area and wherein said controlling device for the heating means is located in the food storage space and mounted on a wall of the cabinet.
